UNITED STATES PATENT OFFICE.

JOHN J. DRIVER, OF ST. LOUIS, MISSOURI.

PLANE.

SPECIFICATION forming part of Letters Patent No. 405,540, dated June 18, 1889.

Application filed December 5, 1888. Serial No. 292,703. (No model.)

To all whom it may concern:

Be it known that I, JOHN J. DRIVER, a citizen of the United States, residing at St. Louis, in the State of Missouri, have invented 5 certain new and useful Improvements in Planes, of which the following is such a full, clear, and exact description as will enable any one skilled in the art to which it appertains to make and use the same, reference 10 being had to the accompanying drawings, forming part of this specification.

My invention relates to handles for planes, whereby the same can be manipulated by persons when standing to plane floors and the 15 like, obviating the necessity of getting down on the knees.

The invention consists in features and details of construction which will now be set forth at length, and then particularly pointed 20 out in the claims making a part hereof.

Figure 1 is a side elevation of a plane having my handle applied thereto. Fig. 2 is a plan view of the same. Fig. 3 is a longitudinal sectional view of the same. Fig. 4 is a 25 view showing the handle only. Fig. 5 is a section on the line 5 5 of Fig. 4. Fig. 6 is a section of a detail.

The same figures of reference indicate the 30 same parts throughout the various views.

5 is the plane, which is of any ordinary construction and preferably made of metal.

6 is the cutter-blade, which is adjusted in said plane by any ordinary means. This means makes no part of my invention. I extend the metal sides of the plane to form ears 35 7 at each side of said plane, and to these ears 7, I journal my handle by a bolt 8, which passes through said handle and said ears.

The handle is preferably made of a bow-shaped piece 9, which has a screw-threaded socket 10 at its top and middle. This screw-threaded socket receives, preferably, a rod or pipe 11, screw-threaded at both ends, of any desired length, which may be joined to a second piece of pipe 12 to form the handle. The pipes or rods 11 and 12 are joined together by a nut 13, having a right and left hand screw-thread, so that when the nut is screwed down the ends of the rods 11 and 12 are brought 45 50 together and make a tight joint. To the pipe

12 is swiveled at the point 13' a handle 14, so that said handle 14 may be turned at any angle. Upon the pipe or rod 12 is also a second handle 15, which is made so as to be adjustable along said rod to accommodate the person using the plane. This handle 15 is made up of a screw-threaded bolt 16, which passes through the wooden part 15 of the handle, and has an eye 18 for receiving the rod 12. By screwing the wooden part 15 in one or the other direction it can be made to approach or recede from the rod 12, and thus allow said handle to be moved along said rod or fastened securely to the same at any point. The handle 14 is for one hand of the user and the handle 15 for the other hand. The ears 7 are about midway between the cutting-line 19 and the heel 20 of the plane, in order that the handle may be attached to the plane at a point midway between 19 and 20, so as to equalize 60 the pressure at the point 19 and the point 20. If the handle were attached to the plane farther back, too much pressure would be thrown upon the heel 20 of the plane and too little pressure put upon the cutting-line 19. So, too, if the handle were attached farther forward of the plane too much pressure would be applied along the cutting-line. 65 70 75

The bolt 8 can be readily removed when it is desired to take the handle off of the plane 80 and use it as an ordinary plane. Said handle can be made of any length by joining together any number of sections 11 and 12.

By the means described floors and other objects can be planed by persons when standing 85 as readily as when upon the knees and with much less fatigue.

The invention is simple and effective, the construction strong and of small cost.

21 is the ordinary handle of the plane, which 90 is fastened to said plane by screws 22 and 23, and may be removed from the plane, if in the way, when the other handle is attached.

Having fully set forth my invention, what I desire to claim and secure by Letters Patent 95 of the United States as my invention is—

1. A handle for planes, consisting of the bow-shaped part 9, having screw-threaded socket 10, one or more screw-threaded rods joined to the same, a handle 14, swiveled to 100

the upper end of said rods, and a handle 15, adjustably secured along said rods, for the purpose described.

2. The combination, with a plane, as herein set forth, of the ears 7, a bow-shaped piece 9, swiveled to said ears 7 by a bolt 8, screw-threaded socket 10 upon said bow-shaped piece, screw-threaded rod 11, adapted to be inserted in said socket 10, a second screw-threaded rod 12, a nut 13, having right and left hand screw-threads thereon for joining the rods 11 and 12 together, a handle 14, swiv-

eled to said rod 12, and a handle 15, adjustable along said rod 12, substantially as and for the purpose described.

In testimony whereof I have hereunto set my hand and affixed my seal, this 3d day of December, 1888, in the presence of the two subscribing witnesses.

JOHN J. DRIVER. [L. S.]
